[57] CLAIM

The ornamental design for a receiver front panel assembly, substantially as shown and described.

DESCRIPTION

FIG. 1 is a front, top and left side perspective view of receiver front panel assembly showing our new design as adapted for an audio-video receiver, with the broken line structure being purely environmental and forming no part of the claimed design;

FIG. 2 is a front elevational view thereof;

FIG. 3 is a right side elevational view thereof;

FIG. 4 is a left side elevational view thereof;

FIG. 5 is a top plan view thereof; and

FIG. 6 is a bottom plan view thereof.

FIG. 7 is a view similar to that of FIG. 1 of a second embodiment of a receiver front panel assembly showing our new design as adapted for an audio receiver;

FIG. 8 is a front elevational view thereof;

FIG. 9 is a right side elevational view thereof;

FIG. 10 is a left side elevational view thereof;

FIG. 11 is a top plan view thereof; and

FIG. 12 is a bottom plan view thereof.
